UNITED STATES PATENT OFFICE.

CURRY ORA WALPER, OF DETROIT, MICHIGAN, ASSIGNOR OF ONE-THIRD TO FRANK A. MASLEN AND ONE-THIRD TO BERNARD E. CLARK, BOTH OF DETROIT, MICHIGAN.

WORK-HOLDING STAND.

Application filed July 24, 1922. Serial No. 576,937.

To all whom it may concern:

Be it known that I, CURRY ORA WALPER, a citizen of the United States of America, residing at Detroit, in the county of Wayne 5 and State of Michigan, have invented certain new and useful Improvements in Work-Holding Stands, of which the following is a specification, reference being had therein to the accompanying drawings.

10 This invention relates to work holding stands. It has for its principal object to provide a simple compact and effective support adapted to hold a wall board in place for sawing, especially that type of wall 15 board in which there is a plastic composition center.

A further object of the invention is to provide a clamping means to hold the work in place.

20 Other objects will appear in connection with the description, reference being had to the accompanying drawing, in which

Figure 1 is a top plan view;

Fig. 2 is a side elevation, parts being in 25 section, and

Fig. 3 is a transverse section on the line III—III, looking in the direction indicated by the arrow.

The stand consists of a table 1, the opposite edges of which may be beveled as at 2. A pivot member 3 is secured at opposite sides of each end of the stand and upon these pivot members legs 4 are mounted, suitable nuts 5 being used to hold the legs upon the 35 pivot members in an obvious manner. The pintles 6 secured upon the pivot member 3 may enter a socket in the upper portion of the leg to prevent pivotal movement of the leg while the nut 5 is screwed tightly upon the pivot. A slot 7 extends longitudinally of the table 1 at about its central axis and the top of the slot is reinforced by metal plates 8 secured at opposite edges of the 40 slot.

45 At one end of the table 1, pivot plates 9, 9, are secured to the table to receive a pivot member 10 upon which is mounted a clamping bar 11 which extends substantially the full length of the table. Wear plates 12, 12 are secured at opposite sides of the bar 11 adjacent to the pivot plate 9 and upon the upper surface of the bar is secured a stop member 13 adapted to engage the adjacent 50 end of the table 1 as indicated in Fig. 2 to limit the upper swinging movement of the

bar 11. Secured upon the lower face of the table 1 is a spring member 14 having a projecting portion 15 adapted to engage the outer end of the member 13 when it is in contact with the end of the table 1 to maintain the member 11 in raised position as indicated by dashed lines in Fig. 2.

The clamping bar 11 is slotted for the greater portion of its length as indicated at 16 and upon opposite sides of the slots wear plates 17 are secured within recesses formed in the upper surface of the clamping bar 11. The slot 16 is made to register with the slot 7 when the clamping bar 11 is swung upon its pivot 10 into a position parallel with the upper surface of the table. Guide flanges 18 are formed upon bracket members 19 secured at the end of the table remote from the pivot 10 and the bar 11 has wear plates 20 mounted in recesses on opposite sides of the 70 end adjacent to the flanges 18. A spring catch 21 is secured upon the end of the table 1 opposite the pivot 10 and this spring has its free end beveled as indicated at 22 for engagement with the free end of the clamping bar 11. When the bar 11 is swung downward into a position parallel with the table, it forces the spring latch member outward by coming in contact with the beveled end portion 22. The spring member 21 has a portion 23 substantially parallel with the top of the table 1 which swings inward toward the end of the bar 11 after it has passed out of engagement with the beveled portion, and this portion 23 acts to prevent 85 upward movement of the bar 11. A suitable handle 24 is provided upon the bar 11 preferably at a point near its free end. The table 1 is recessed as indicated at 25 to receive swinging bracket arms 26 of which four are shown in Fig. 1, these bars preferably being of sheet steel of a thickness such that their upper surface is substantially 90 in the same plane with the main upper surface of the table 1.

With the bracket arms 26 swung at substantially right angles to the sides of the table, a sheet of wall board 27 may be placed upon the table and the brackets as indicated by dashed lines in Fig. 1 and the clamping arm 11 will be swung downward upon the upper surface of the board until its free end is engaged beneath the portion 23 of the spring latch 21. A hand saw 28 may then be inserted through the register- 110

ing slots 16 and 7 to sever the wall board or to make an incision of any length desired. The space between the plates 17 will be very little wider than the extreme spread 5 of the saw teeth when set so that the board may be divided very accurately along the line desired.

It will be evident that the legs may readily be removed if desired or that they may 10 be swung to a position parallel with the table 1 when the nuts 5 are loosened and the legs drawn out of engagement with the pintles 6. The stand will then be compact and adapted for easy transportation.

15 It will be obvious that many changes may be made in details of construction without departure from the principle involved or sacrificing any of its advantages. The invention is therefore claimed in any of its 20 forms or modifications within the legitimate and valid scope of the appended claim.

I claim:

25 A work supporting stand comprising a table portion having a slot extending longitudinally thereof, a clamping bar pivoted at one of its ends adjacent to one end of said table portion, the pivotal attachment being such that the clamping bar may be 30 swung into position substantially parallel with the surface of the table, said clamping

bar having a slot longitudinally thereof adapted to be brought into registration with the slot in the table portion by the pivotal movement of the bar, and guiding means adapted to engage said clamping bar near 35 its free end to hold it in position with the slots in registration, the pivotal movement of said bar being adapted to carry it away from the surface of said table portion, and said table portion when said clamping bar 40 has been swung into inoperative position being left free and unobstructed for the placing of work thereupon, the upper surface of the table portion being provided with recesses and pivoted arms mounted 45 within said recesses with their upper surfaces substantially flush with the surface of the table whereby the arms may be swung from a closed position within the table portion to a position substantially at right 50 angles thereto with their upper surfaces forming a continuation of the unobstructed upper surface of the table portion.

In testimony whereof I affix my signature in presence of two witnesses.

CURRY ORA WALPER.
